UNITED STATES PATENT OFFICE.

HAROLD M. LOVELL, OF SOMERVILLE, MASSACHUSETTS.

ROCKING-CHAIR FAN.

1,267,094.

Specification of Letters Patent. Patented May 21, 1918.

Application filed April 13, 1917. Serial No. 161,783.

To all whom it may concern:

Be it known that I, HAROLD M. LOVELL, a citizen of the United States, residing at Somerville, in the county of Middlesex and State of Massachusetts, have invented certain new and useful Improvements in Rocking-Chair Fans; and I do hereby declare the following to be a full, clear, and exact description of the invention, such as will enable others skilled in the art to which it appertains to make and use the same.

This invention relates to improvements in fans for rocking chairs.

The object of this invention is to provide a fan which may be attached to the arm and runner of a rocking chair, whereby upon rocking motion of the chair, the fan will be operated in a vertical plane.

A further object of this invention is to provide a fan for rocking chairs, which may be removably secured to the rocker and arm of the chair and so secured thereto, as to position the fan in front of the occupant of the chair, whereby upon rocking motion of the chair the fan will be moved in a vertical plane, thus keeping the occupant of the chair cool at all times.

A still further object of this invention is to provide a fan for rocking chairs which may be removably secured to the chair and has a novel means for adjusting the fan at any desired angle position in front of the face of the occupant of the chair so that upon rocking the chair, the fan will be moved in a vertical plane, causing a circulation of air, thus keeping the occupant of the chair cool at a comparatively small amount of energy.

A still further object of this invention is to provide an attachment for rocking chairs, which includes a tube to which are secured brackets, which brackets are removably secured to one arm and rocker of the chair and slidably arranged in the tube is a reciprocating bar, which has a loose connection with an operating member, which is located in the lower end of the tube, a head removably secured to the upper end of the tube and surrounding the reciprocating bar, a fan carried by the head, said fan being adjustable and the head being movable in a horizontal plane to permit the fan to be turned out of the way when not in use and upon the rocking of the chair, the operating member will force the rod or bar upwardly and cause the fan to move upwardly and when the chair is

moved rearwardly in the rearward rocking motion, the spring means will force the bar downwardly and urge the operating rod outwardly, thus the operation is accomplished upon the rocking of the chair.

A still further object of this invention is the provision of a rocking chair fan of this character, which will be simple, practical, and comparatively inexpensive in construction, and one that can be manufactured and sold at a low cost.

With these and other objects in view, the invention consists in the novel combination and arrangement of parts hereinafter more fully described and set forth in the claims hereto appended.

In the drawings:

Figure 1 is a front elevation of a rocking chair illustrating my improved fan attachment thereto,

Fig. 2 is a side elevation of the same,

Fig. 3 is a vertical sectional view taken through the fan attachment,

Fig. 4 is a sectional view taken on the line 4—4 of Fig. 1,

Fig. 5 is a top plan view of the fan attachment,

Fig. 6 is a sectional view taken on the line 6—6 of Fig. 3,

Fig. 7 is a sectional view illustrating one of the attaching brackets,

Fig. 8 is a sectional view taken on the line 8—8 of Fig. 3.

Like numerals of reference designate corresponding parts in all the figures of the drawings.

Referring more particularly to the drawings, the numeral 1 designates a rocking chair in its entirety and it may be of any desired construction, but it is here shown as having a seat 2, rockers 3, back 4 and arms 5, and to this rocking chair my improved attachment is applied.

My improved attachment comprises a relatively long tube or sleeve 6, which has one end provided with an annular flange 7 on the exterior thereof, the opposite end being fully open as shown. The lower end of the tube or sleeve 6 has its bore reduced as at 8 to provide a bearing bushing, the purpose of which will be hereinafter more fully described.

The reducing of the bore of the sleeve or tube 6 adjacent the lower end forms an interior annular shoulder 9, which is substantially horizontal.

An operating member 10 is slidably arranged in the reduced bore 11 of the sleeve or tube 6, and has its inner end provided with annular flange 12, which rests upon the horizontal shoulder 9 in the sleeve 6, thus preventing the operating member or rod 10 from being entirely withdrawn from the tube or sleeve 6. The outer end of the rod 10 is provided with an enlarged head 13, which has its convex outer surface 14 which constitutes a wear plate and is adapted to have engagement with the floor or other surface when the chair is rocked forward, the purpose of which will be hereinafter more fully described.

A coiled spring 15 has one end secured to the upper surface of the flange 12 on the inner end of the operating rod 10 and its opposite end is secured to the flange 16, carried on the lower end of the reciprocating bar 17, which is slidably arranged in the tube or sleeve 6. The upper end of the reciprocating bar 17 extends upwardly beyond the upper edge of the tube 6 as illustrated.

The connection of the ends of the spring 15 to the flanges 16 and 17 of the rod 10 and bar 17 provides a loose connection between these two members, and also serves as a buffer when the device is in operation.

A pin 18 is arranged to extend transversely through the bar 17 adjacent the lower end thereof and in close proximity to the flanged inner end 16. The pin 18 has its ends projecting beyond the surface of the walls of the bar 17 and is adapted to have engagement with the underside of the stop washer 19, which is slidably arranged on the bar 17.

A second stop washer 20 is rigidly secured to the tube 6 on the interior thereof intermediate its ends by the transversely extending pins 21, which are arranged in spaced relation to one another and extend through the periphery of the washer 20 and out through the tube as shown in Fig. 6, thus the stop washer 20 is rigidly secured within the sleeve or tube 6 centrally thereof and in spaced relation to the inner end of the bar 17 as illustrated.

A coiled spring 22 surrounds the bar 17 and is located between the washers 19 and 20. One end of the spring is secured to the upper surface of the washer 19, while its opposite end is secured to the under side of the stop washer 20, thus when the operating rod 10 is forced inwardly, the bar 17 forced upwardly, the spring will be compressed, and when the operating rod 10 is out of engagement with the surface or floor, the spring 22 will urge the rod 17 downwardly, forcing the operating rod 10 outwardly, into engagement with the floor surface in the next operation.

A bearing head 23 is provided with a vertical bore 24, which has its lower portion enlarged as at 25 to form a substantially

horizontal shoulder 26, which is adapted to engage the upper edge of the tube or sleeve 6 when the bearing head 23 is fitted thereon as illustrated. The bearing head 23 is rotatably mounted on the upper edge of the tube 70 or sleeve 6 and has its upper portion enlarged as at 27 provided with a reduced bore 28 through which the upper end of the bar 17 extends. The bar 17 extends upwardly beyond the upper surface of the bearing 75 head 23 as shown and the purpose of the same will be hereinafter more fully described.

A vertical projection 29 is formed on the upper surface of the bearing head 23 on the periphery thereof and is adapted to have pivotally secured thereto, an arm 30. The arm 30 has one end pivotally secured to one side face and at the upper end thereof to the projection 29 by the pin 31, and its opposite end is pivotally secured between the arms 32, which are formed by bifurcating one end of the supporting member 33. The arms 32 of the supporting member 33 are arranged on opposite sides of the free end of the arm 30 90 and pivotally secured thereto by a pin 34, which extends transversely through the arms 32 and the arm 30 and has secured on its outer end, an adjustable nut 35, which secures the same thereto, and thus it can be 95 seen that the arm 30 and operating member 33 are hingedly connected together.

A link 36 is provided with a longitudinally extending slot 37 and has secured to its lower longitudinal edge adjacent one end, the cap 38, which is rigidly secured to the upper end of the operating bar 17 as shown, and the link is pivotally secured to the arm 30 by the pin 39 which extends through the slot 37 into the arm 30 as shown, whereby when 105 the rod is forced upwardly, the pin will be moved in the slot and the arm 30 will be raised on its pivotal point 31, which constitutes a fulcrum, will raise the supporting member 33 upwardly, the purpose of which 110 will be hereinafter more fully described.

It is understood that the nut 35 is tightened so as to cause the arm 30 and supporting member 33 to move simultaneously, but when it is desired to move the supporting 115 member 33 vertically with relation to the arm 30, it is only necessary to loosen the nut 35 and swing the member 33 rearwardly, up out of the way of the occupant of the chair when the device is applied thereto.

The bearing head 23 is provided in its wall with an arcuate slot 40, which is adapted to slidably receive a pin 41, which has one end pivotally secured as at 42 to the tube or sleeve 6 and its opposite end extends outwardly through and beyond the surface of the walls of the slot 40 and is screwthreaded as at 43 and receives removably fitted thereon, the wing nut 44, thus it can be seen that the bearing head can be turned in a hori- 120 125 130

zontal plane to move the arms and supporting member out of the way so that the occupant may get into and out of the chair when desired.

5 When it is desired to use the device, the nut 44 is tightened on the bolt 43, thus the head 23 is held in any desired position with relation to the tube or sleeve 6.

A substantially U-shaped supporting yoke 10 45 has its arms removably secured to the opposite sides of the supporting member 33 adjacent the outer end thereof by the removable screws 46 or other suitable fastening means, thus positioning the web at a relatively spaced distance from the upper surface of the supporting member.

A horizontal arm 47 is slidably arranged on the upper surface of the supporting member 33 and between the web of the supporting yoke 45, the wear plate 48 being arranged between the under side of the web 45 and the upper side of the supporting arm 47 of the fan and a screw 49 is threaded through the web of the yoke 45 and has its inner end bearing against the wear plate 48, forcing the same into engagement with the upper side of the member 47 to rigidly hold the same on the supporting member 33. A fan 50 is formed integrally with the outer end of the arm 47, thus it can be seen that the fan may be adjusted at any angle with relation to the tube 6 or it may be swung upwardly by unloosening the nut 35 and swinging the supporting member 33 rearwardly and out of the way of the occupant of the chair.

A pair of supporting brackets designated in their entirety by the numeral 51 comprise the clamping rings 52, which have their free ends arranged in spaced parallel relation as at 53 and the rings 52 are arranged around the tube 6. A bar 54 has one end arranged between the spaced ends 53 of the rings and secured thereto by a bolt 55, thus securing the same to the tube and sleeve and the arm in position with the one fastening member 55. The opposite end of the arm has formed thereon, the U-shaped clamping member 56, which is adapted to have engagement with the arm 5 or rocker 3 of the chair, as shown and is secured thereon by a wing bolt 57 and the device is ready for use.

In operation, the occupant sits in the chair 55 1, the nut 44 of the bolt 41 is loosened, the head is moved to position the horizontal fan supporting means at any desired position desired by the occupant of the chair, the nut 44 is then tightened against the head, holding the same in this position. The occupant of the chair rocks forward and upon the initial engagement of the bearing surface 14 of the rod 10 in engagement with the floor, it will be forced inwardly forcing the reciprocating bar 17 upwardly which

in turn moves the arm 30 upwardly, raising the fan in a vertical plane about its fulcrum 31 and upon rearward rocking motion when the head 14 leaves the floor, the rod will be forced outwardly by the spring 22 70 and the rod moved downwardly, thus causing the fan to have sweeping action in a vertical plane in front of the occupant.

I claim:

1. A fan operating means comprising a 75 tube or sleeve; brackets removably secured to the tube or sleeve for securing the same to a rocking chair, a bearing head rotatably mounted on one end of the tube, a bar reciprocally mounted through the bearing 80 head and sleeve, an operating member loosely mounted in the lower end of the sleeve, means for loosely connecting the operating member with the reciprocatory bar, a supporting arm pivotally secured to the 85 bearing head, a link pivotally secured to the supporting arm and rigidly secured to the upper end of the reciprocatory bar, and a fan supporting means hingedly and pivotally secured to the outer end of the arm, as 90 and for the purpose specified.

2. A fan operating means comprising a tube or sleeve, an operating member reciprocally mounted in the lower end of the sleeve, a wear plate having a convex surface 95 formed on the outer end of the operating member, a reciprocatory bar mounted in said tube or sleeve, a spring connecting the inner end of the bar with the inner end of the operating member, a bearing head rotatably mounted on the upper end of the sleeve and surrounding said bar, means carried by the tube and engaging the bearing head and holding the same against rotary movement with relation thereto, a projection carried by the head, an arm pivotally secured to the projection, a link pivotally secured to the arm and rigidly secured to the upper edge of the bar, a supporting member hingedly secured to the outer end 105 of the arm, a yoke carried by the supporting member, a fan carrying arm adjustably secured to the yoke and supporting member, and brackets secured to the tube to facilitate the securing of the device to a 110 rocking chair, as and for the purpose specified.

3. A fan operating means comprising a tube having its lower end reduced in the interior thereof, to provide a substantially 120 horizontal shoulder, an operating member slidably arranged in the tube and having its inner end flanged to engage the shoulder for preventing the removal of the operating member therefrom, the outer end of said operating member provided with a convex surface to constitute a wear plate, a spring secured to the inner flanged end of said member, a reciprocatory bar slidably arranged in the tube and having its inner end 125 130

4

flanged and secured to the free end of the spring for forming a resilient connection between the operating member and bar, a head rotatably mounted on the upper end 5 of the tube, means for holding the head against rotation with relation to the tube, a vertical projection formed on the head, an arm pivotally secured to the projection, a link rigidly secured to the bar and piv- 10 otally secured to the arm, a supporting member pivotally secured to the free end of the arm, a yoke carried by the supporting member, a fan adjustably carried by the yoke and supporting member, a spring 15 surrounding said operating bar, means for holding the spring against longitudinal sliding movement on the bar, said spring adapted to be compressed on the inward movement of the operating member and upon release of pressure by the operating 20 member, the spring will force the reciprocating bar downwardly in the tube, and brackets secured to the tube for securing the same to a rocking chair, as and for the purpose specified. 25

In testimony whereof I affix by signature in presence of two witnesses.

HAROLD M. LOVELL.
